UNITED STATES PATENT OFFICE

100,142

DESIGN FOR A FINGER RING BOX OR SIMILAR ARTICLE

Jack G. Allen, Chicago, Ill., assignor to F. H.
Noble & Co., Chicago, Ill., a corporation of Illinois

Application April 24, 1936, Serial No. 62,295

Term of patent 7 years

To all whom it may concern:

Be it known that I, Jack G. Allen, a citizen of the United States, residing at Chicago, in the county of Cook, State of Illinois, have invented a new, original, and ornamental Design for a Finger Ring Box or Similar Article, of which the following is a specification, reference being had to the accompanying drawing, forming a part thereof.

In the drawing, Fig. 1 is a top plan view of a finger ring box or similar article showing my new design;

Figs. 2 and 3 are, respectively, front and side elevations of the same; and

Fig. 4 is a perspective view of said box.

I claim:

The ornamental design for a finger ring box or similar article.

JACK G. ALLEN.

CERTIFICATE OF CORRECTION.

sign No. 100,142.

June 23, 1936.

JACK G. ALLEN.

It is hereby certified that error appears in the printed specification of the above numbered patent requiring correction as follows: Second column, line 8, in the claim, after "article" and before the period insert the words, as shown; and that the said Letters Patent should be read with this correction therein that the same may conform to the record of the case in the Patent Office.

Signed and sealed this 15th day of September, A. D. 1936.

Henry Van Arsdale
Acting Commissioner of Patents.
